COVER UNIT FOR A POCKET KNIFE AND A PROCESS FOR MAKING THE SAME

Albert M. Baer, New York, N.Y., assignor to Imperial Knife Company, Inc., Providence, R.I., a corporation of Rhode Island

Application February 20, 1956, Serial No. 566,435

1 Claim. (Cl. 41—22)

This invention relates to a cover unit for a pocket knife and to a process for making the same. More particularly the invention is concerned with an ornamental knife cover unit and its method of manufacture.

One of the most common ornamental effects present in a knife cover unit is that obtained by providing the scale with areas of different predetermined shapes and colors, and it is to a unit so ornamented that the present invention relates.

One typical example of this ornamental effect is a silver shield on a monochrome background. Another is the group of rivet heads that constitute the visible parts of rivets which in the past were used to hold a scale to a knife. Replicas of these heads still are present on some knives for ornamental effect alone, the rivets having been eliminated. Still another example is a metal band that transversely spans a scale.

This ornamental effect can be secured in many different ways, for instance, by securing a metal member on the outer surface of a thick scale member, or by forming an opening of suitable shape in a thin opaque plastic sheet that is wrapped around a sheet metal support and locating in the opening a protuberance carried by the support, or by molding an intaglio impression of the desired contour in the underpart of a thick, stiff transparent cover, silvering the impression and applying a different color to the undersurface of the balance of the cover.

To secure the ornamental effect requires substantial additional manufacturing costs in added parts, labor, machines and dies, and therefore materially increases the cost of a knife without enhancing its durability or efficiency.

It is the primary object of the present invention to provide a cover unit and method of the character described which avoid the foregoing difficulties and enable the dress of a knife to simulate any one of the old embodiments of the aforesaid ornamental effect for but a slight additional manufacturing cost.

It is another object of the invention to provide a cover unit and method of the character described which enable new and almost limitless embodiments of said effect to be obtained without appreciable increase in cost.

It is another object of the invention to provide a cover unit and method of the character described which create a highly realistic ornamental effect that to casual observers realistically simulates the original ornamental construction, e.g., the actual shield, rivet heads or metal band.

It is another object of the invention to provide a cover unit and method of the character described which create an ornamental effect cheaply and simply and in such a location that it cannot, either accidentally or by design, be scratched or worn.

It is another object of the invention to provide a method of the character described which is simple and inexpensive to practice and lends itself to mass production.

Another object of the present invention is to provide

2

a method of the character described whereby a durable and rugged ornamental cover unit is produced.

Still another object of the invention is to provide a pocket knife having a cover unit of the character described which is simple and inexpensive to manufacture.

Other objects of the invention in part will be obvious and in part, will be pointed out hereinafter.

The invention accordingly, consists in the features of construction, combinations of elements, arrangements of parts and series of steps which will be exemplified in the device and process hereinafter described, and of which the scope of application will be indicated in the appended claim.

In the accompanying drawings in which is shown one of the various possible embodiments of the invention,

Fig. 1 is a side view of a pocket knife having an ornamental cover unit constructed in accordance with the invention;

Fig. 2 is a bottom view of the pocket knife shown in Fig. 1;

Fig. 3 is a perspective view of a cover unit embodying the invention, a portion of the outer sheet being broken away;

Fig. 4 is an enlarged sectional view taken substantially along the line 4—4 of Fig. 3;

Fig. 5 is an exploded view of the cover unit shown in Fig. 3, the cover sheet being shown opened out;

Fig. 6 is a schematic perspective view of a printing press employed in the method of producing a decorative cover unit of the character described; and

Fig. 7 is a schematic perspective view of a cutting tool employed in the method of the instant invention.

Generally, the objects of the invention are carried out by drumtightly stretching across the external surface of

a scale a transparent plastic sheet having a suitably colored undersurface preferably including one or more uncolored areas. The invention will be described with respect to the production of a cover unit having a transversely extending simulated metal band, although the method can be used to produce any desired ornamental effect. In order to obtain a cover unit which truly appears to have the design on the outside of the unit, the sheet must be tightly held against the scale so that the bright scale surface seen through the transparent portion of the clear plastic sheet will not appear to be beneath the same, but will seem to be in the same plane as the sheet itself.

Moreover, the color or design should be on the surface thereof which faces the scale in order to obtain the illusion that both the color and the external surface of the scale are a continuous single surface. This also prevents the design and color from being scratched or worn. Preferably the scale is arched, conventionally transversely, so that when the sheet is transversely stretched across the scale its undersurface will intimately contact the external surface of the scale to heighten the illusion that the coloring material and scale surface are in a common plane.

Referring now in detail to the drawings, the reference numeral 10 denotes a pocket knife having cover units constructed in accordance with the invention. The knife includes a conventional metal frame 12, a metal liner 14 being provided on each side thereof. A cover unit 16 is superimposed on each liner at the outside thereof, and blades 17 are located in the frame. The cover units are secured to the frame in any accepted manner, as, for example, by ears 18 at the ends of the cover unit received in pockets 19 at the ends of the metal liners.

Each cover unit comprises a transversely arched, elongated sheet metal scale 20 with a bright external surface and a clear transparent plastic sheet 22, fabricated, for example, from a thermoplastic, e.g., cellulose acetate. The sheet includes marginal edge portions 23 the pur-

pose of which will become apparent hereinafter. At each end of the scale on the external surface thereof a raised bolster 24 is provided integrally therewith, each bolster including a rib 28 adjacent the intermediate external surface 26 of the scale.

In the knife shown herein, and pursuant to a feature of the instant invention, a central, transverse, transparent section 30 is provided in the sheet 22. The portions 32, 34 of the sheet on each side of said section may be of different color from one another or have different designs, the color or designs being provided on the undersurface of the sheet, i.e., the surface which is to face the scale.

The sheets 22 are drumtightly held stretched across the external surface 26 of the scale between the bolsters 24 in the manner shown and described in United States Letters Patent No. 2,689,400 issued September 21, 1954 and owned by the assignee of the present application. Briefly, the process of attachment is as follows: The sheet is placed on the intermediate external surface 26 of the scale, and the marginal edge portions 23 of the sheet are folded around the lateral edges of the scale and brought beneath the same. The folds are locally plasticized, as by the application of heat and pressure while the sheet is under tension, so as to permanently set the folds, and so that upon deplasticization a controlled, slight, transverse shrinkage of the sheet will take place whereby to stretch the sheet drumtightly across the scale. When the sheet is tightly held to the scale, there will appear to be a bright metal band across the cover unit in the region of the central, transverse, transparent band 30, this effect being created by the intimate contact between the sheet and scale, the slight thickness of the sheet, and the smooth stretched surface of the sheet. In this way an article accomplishing the objects of the invention is produced.

The sheets 22 conveniently are produced from a large panel 36 of thermoplastic which is printed with the desired colors or design in a roller printing press 38 (see Fig. 6). The press includes rollers 40 which have annular, equally spaced grooves 42 disposed between the ends thereof. The grooves form non-printing areas that divide the rollers into printing surfaces 44. The printing surfaces can be adapted to print designs, and the color of the ink supplied thereto can be varied to permit printing of different colors.

For a reason to be made apparent hereinafter, the distance between every other groove 42 is slightly greater than the length of the intermediate surface 26 of the particular scale with which the sheet being fabricated is to be used. The printing process produces a panel having a plurality of clear transparent bands 46 corresponding to the grooves; the areas 48 between said sections have various colors or designs printed thereon.

The sheets are stamped out of the panel by a steel rule die 50. The cutting edge 52 of said die has a length and shape corresponding to the desired length and shape of the sheet 22 to be produced.

The die is used by placing it transversely on the panel between alternate transparent sections 46 and forcing its cutting edge through the strip. For this purpose the die may be mounted in a press such as is conventionally used in connection with steel rule cutting dies. Inasmuch as the length of a given die is the same as that of the intermediate external surface 26 of the scale for which said die is adapted to produce sheets, the steel

die can be placed on the panel transversely between alternate bands 46. Thus, each cutting by the die will produce a sheet having a central, transverse, transparent band and two separate colored sections on each side thereof. Several dies of the character just described may, of course, be used simultaneously to produce a cutting tool extending across the entire width of the panel and, optionally, the entire length thereof. In this way many sheets 22 may be stamped out at the same time.

It will be appreciated that by varying the color of the ink supplied to the rollers, or by varying the design, the rollers can be adapted to print a great variety of ornamented sheets. This can be accomplished in the same printing press by using different colors and designs for the various printing surfaces thereof. The distance between annular grooves can also be varied to produce more than one transparent band on the resulting sheets. Still further, the grooves can be made slanting or longitudinal on the roller instead of annular so that slanting and longitudinal transparent bands are produced in the sheets. And, of course, the process described above can be employed to produce sheets of diverse sizes and shapes to fit corresponding scales.

Pursuant to the general objects of the invention, the external surface of the scale may be given any desired color and the sheet provided with a transparent section corresponding to the part of the design in which the color of the scale is to appear. In this way, moreover, different design combinations can be produced at a low cost. It will be readily appreciated that the transparent areas may be shaped to simulate rivet heads and shields so as to produce the appearance of the other examples hereinabove described.

It thus will be seen that there are provided a device and method for making the same which achieve the several objects of the invention, and are well adapted to meet the conditions of practical use.

As various possible embodiments might be made of the above invention, and as various changes might be made in the embodiment above set forth, it is to be understood that all matter herein described, and shown in the accompanying drawings, is to be interpreted as illustrative and not in a limiting sense.

Having thus described my invention, I claim as new and desire to secure by Letters Patent:

A decorative cover unit for a knife, said unit having a simulated metal design area in its surface and including a metal member having an outwardly convex polished external surface, and a thin flexible plastic sheet overlying said external surface, the marginal edge portions of said sheet being turned under the edges of said member and said sheet being tensed thereon so as to be in intimate contact therewith without a bond therebetween, said sheet having a colorless, transparent section disposed adjacent a portion having an opaque color on the undersurface thereof different from that of said external surface so that said transparent section will show a reflected metallic design area in the shape of said section and seemingly a part of the sheet.
